UNITED STATES PATENT OFFICE.

JOSEPH H. THERIEN, OF SAN FRANCISCO, CALIFORNIA.

MANGLE.

1,181,087.

specification of Letters Patent. Patented Apr. 25, 1916.

Application filed September 6, 1907. Serial No. 391,721.

To all whom it may concern:

Be it known that I, JOSEPH HILAIRE THERIEN, a citizen of the United States, and resident of the city of San Francisco, in the county of San Francisco and State of California, have invented certain new and useful Improvements in Mangles, of which the following is a specification.

The invention contemplates improvements in that class of machines which are employed for pressing, smoothing, and surfacing or ironing bed and table linen, and such articles of personal wear or furnishings as are made of a washable fabric. Among other things, it is sought to provide a simple and practical means wherewith the operator of the machine, whether skilled or unskilled, can have easy and perfect control over the application of pressure between the mangling media—which in the herein described embodiment of the invention preferably consist of two rolls, a heated roll and a padded roll, although the same means may be applicable as well to other mangling instruments. With particular reference to the roll first named, it is fitted with a calcactive device of special design, calculated to insure economic generation of heat and its even diffusion throughout the roll and thereby to enable the user thereof to turn out work of superior grade, due to the combining of the requisite degree of calcic with the proper degree of pressure in the operation of the mangle.

Further, the invention comprises a feed table of peculiar construction, for spreading the linen as it is pushed toward or drawn by the rolls or equivalent mangling instruments; also a guard to protect the hands and fingers of the operator while engaged in feeding the linen to the rolls; and generally speaking, a combination of novel or improved features of construction all aiming to produce at moderate cost a machine which will be effective, reliable and convenient.

Referring to the accompanying drawings, Figure 1 is an end view of the mangle. Fig. 2 is a vertical transverse section on the line 2--2 of Fig. 3, looking in the direction of the arrows. Fig. 3 is a front elevation, with the upper part thereof in section, which is on the line 3--3, Fig. 1, looking to the left. Fig. 4 is a top view. Figs. 5 and 6 are detail views showing a modification of the heating device illustrated in Fig. 3.

In the form selected for illustration, the mangle constituting the subject matter hereof has a chair-like frame consisting of two opposite members 1 and 2, united by a central bar 3, and tie-rods 4. Two head-supports 5 and 6, facing each other from the opposite ends of the frame, are mounted upon arms 7 and 8 of the latter. These supports may be plate castings flanged for bolting at the base, as at 9, Fig. 2, and joined one to the other at the front edge near the top by a cross-bar 10.

Within and between the head-supports 5 and 6, are placed the aforementioned mangling-rolls, herein designated by the numerals 11 and 12. These rolls are arranged one above the other, as illustrated, and constitute the agencies for imparting heat and pressure to the goods operated upon in this improved mangle. By preference, the upper roll is made the heat transmitting medium, and the lower roll, the instrument with which the pressure is applied. The former therefore will be made of metal, conveniently steel tubing, sufficiently smooth or polished to adapt it to surfacing or ironing the goods; and the latter, which also may be a tube, will be covered with a suitable padding 13. The two rolls can be put in the machine or removed therefrom as may be required, through large openings 14 and 15, respectively provided therefor in the head-supports 5 and 6. The roll 11 is shrunk upon conical heads or bushings 16, the outer ends of which are turned to form journals 17 for the roll. These journals have their bearings in disks 18, held by set-screws 19 within the openings 14 and provided with oil-tubes 20. The roll 12 is shrunk upon bushings or heads 21, which terminate in journals 22 that project through the openings 15.

Two levers 23 are employed to carry up, hold, and press the lower roll against the upper roll and the goods or articles that are passed therebetween. These levers are yieldingly fulcrumed, the arrangement therefor comprising a wedge-like rocker or bearing-piece 24 projecting from the under side of each lever; a vertically-movable seat 25 with a V-shaped notch 26 in its surface adapted to receive the rocker or bearing piece and within which the latter can oscillate; and a short, stout, spiral spring 27 placed under the seat and lodged in a recess formed by the bottom flange 9 and re-

taining guides or ribs 28 on the inside of the supports 5 and 6, forwardly. The spring is coiled around a stem 29 depending from the seat and passing through a suitable hole in the flange 9. The journals or spindles of the lower roll are fitted to suitable bearings each in a curved portion 30 of its respective lever-arm, the short arm as shown. The other or long lever-arm is connected by a 5 rack 31 to a handle-bar 32, pivoted to the frame of the machine, and adapted for engagement with a rack 33 secured to the forward part of the frame. The levers 23 are interconnected by a rod 34, passing through lugs 35, as suggested in Fig. 2, and above this rod the levers are further joined together by a wide board 36, resting upon them forwardly of the lower roll and constituting the feed-table over which the 10 clothes are spread preparatively to being taken up by the rolls.

It will now be seen that the operator, by a simple oscillation of the levers, on their yielding fulcrum, is enabled to move the lower roll toward or away from the upper roll and increase or decrease to whatever extent he may see fit the relative proximity of or the intervening space between the rolls, graduating their contact or gaging the distance at which they should remain one from the other, in the proper ratio to the thickness of fabric intended to be pressed by and between them, whether thin or otherwise, and whether passed in single or double 15 thicknesses or in plural folds. The rolls can thus be brought together or put apart quickly, to suit either normal or abnormal conditions. It is further apparent that the arrangement shown and described permits the use of a spring force which shall be adequate for producing any desirable pressure between the rolls, irrespective of the working distance at which they are set. No special means are or need be provided to 20 augment or diminish the strength of the springs by tension or relaxation, and consequently there is nothing for the operator to mind but the adjustment of the lever system and feed-table connected therewith, 25 in so far as the application of pressure is concerned. The pressure can be regulated by depressing the handle-bars 32 one or more notches at a time along the racks 33. This leaves the resiliency of the springs unaltered, and the rolls upon which they exert their force are held yieldingly together at the tightest setting, the rolls retaining at all times a fit measure of self-accommodation 30 to varying thicknesses of the goods passing between them.

It is deemed preferable to turn both the coming-roll and the pressure-roll in the operation of the machine (in the form disclosed herein). It is also preferred that the 35 two rolls be rotated positively together at

even speed, in order to avoid any possible dragging and tearing of the clothes while they are being pulled and compressed between the rolls. With this object in view, the adjacent spindles of the rolls are provided with gear-wheels of equal dimensions, 37 and 38, at one end, conveniently the right as shown, these gears being arranged to intermesh as the lower roll is moved toward the upper roll while being adjusted for work. To rotate the rolls, another gear-wheel 39 is provided on the left-hand spindle of the upper roll and made to mesh with a pinion 40, mounted in front thereof on a sleeve adapted to rotate upon the cross-bar 40. This sleeve is cast integral with the pinion and is cut into three sections, 41, 42, 43. The sections 41 and 42 are slideable upon the cross-bar and formed so as to constitute co-acting clutch-members, which are 45 normally separated by a spiral spring 44 coiled around them. The section 43 on the contrary is fixed to the cross-bar 10 by a set-screw 45, forming an abutment for a lever 46, pivotally mounted on the same shaft 40 and adapted to throw the clutch-members into engagement. For the latter purpose, the sleeve section 43 is provided on opposite sides with cam-faced portions 47, and the lever 46 is supplied with straight-edged 50 knife-like projections 48, which engage the said parts 47 and work the clutch against the pressure of the spring, upon the lever being raised. The fixed sleeve section has notches 49, which receive the projections of 55 the lever after it is raised, and by holding it in its perpendicular position operate to keep the slideable sleeve sections in clutch and consequently adapted to rotate together. A split pulley 50 is mounted on the sleeve 60 section 42, and this is connected by a belt 51 with a smaller pulley 52, secured to a sleeve 53, on the outer end of the central bar 3. The latter-named sleeve also carries a pulley 54, belted to any suitable prime 65 mover.

Fuel-gas is probably the most available and economical combustible to employ with which to heat the upper roll, and therefore this roll is furnished with a combustion-pipe 115 55, passing longitudinally through its center and through the journals 17, which are made hollow for the purpose. The pipe 55 is supported at the ends by brackets 56, 57, and secured in place by a set-screw 58. It 120 is supplied with gas and air, the latter under a forced draft, through a fitting having inlets 59 and 60, which are inclined one with relation to the other and connected by suitable nipples, 61, 62, with a gas-cock 63 and an air-cock 64, respectively. The portion of the pipe that lies within the roll is partly cut or sawed across, substantially at right angles to its axis, to produce a series 125 of segmental slits or kerfs in its surface, 130

through which the gas will flow and when lighted will shoot forth a succession of parallel and laterally expanding flames against a wide area of the inner circumference of the rotating upper roll, thereby heating it quickly and in a most effective manner. In mangling-rolls of minor dimensions, up to about 34 inches in length, the said slits or kerfs may be of uniform size throughout, as shown at 65, Fig. 3. In the longer rolls, these slits or kerfs had better be graduated, the same increasing in length or depth from each end of the roll toward the center thereof, as illustrated at 66, in Fig. 5, which construction is suitable for rolls of all lengths. This Fig. 5 also shows a fitting with three inlets, 59, 60, and 67, the third one being provided in case it should be desired to use two jets of air in connection with the gas jet. If only one air jet is employed, the other one can be stopped by a suitable cock, as will be understood. Both air-inlets are inclined relatively to the gas-inlet, as Fig. 5 shows. Fig. 6 gives a separate view of the last-mentioned fitting, showing it in a different position.

Provision is made to let out the fumes from the burnt gas in the roll 11, by making apertures 68 in the conical parts of the heads 30 or bushings 16, which owing to their inclined faces lead the fumes and soot away from the clothes that reach the ends of the roll while passing the same during the mangling operation. The heat from these fumes and the burning gas is turned back and diverted from the adjacent disks, oil-tubes, etc., by deflectors 69, which may consist of cast-iron washers or equivalent devices.

The feed board or table 36, as before stated, rests upon the levers 23, to which it is firmly secured. It may therefore be considered a part of the lever system (or vice versa the lever system a part of the table), they being oscillated together by rocking upon the yielding supports, so that the table becomes inclined or is leveled according as the levers are swung up or down to adjust the rolls for work. As the lower roll is suspended by its journals in the lever-arms, it also partakes of the same movements and bears a constant relation to the table, whose position relative to the lower roll is undisturbed by any movement of the levers, which insures regularity in the feeding. The outer edge of the table, it will be seen, facilitates the feeding to the rolls of the larger linen that bears against it, by causing it to spread as it is first pushed in toward the rolls and subsequently drawn in by the joint action of the rolls thereon.

After passing the rolls, the clothes may be allowed to fall into a chute or rearwardly-inclined receiver 70, which extends down, in 65 a suitable curve, from the upper part of the

chair-like frame of the mangle to a point within reach of the operator, who is thereby enabled to look over the pressed clothes, take care of the same, and if necessary pass them a second and third time through the machine, as may be required. This chute or receiver is conveniently made of galvanized sheet-steel, riveted at the sides to curved channel-irons 71, and at the top and bottom to angle-irons 72. Centrally, it rests upon the upper forward rod 4 of the framework, and at the upper end it is held by hooks 73, formed on the channel-irons 71.

A second table 74 is placed in rear of the rolls whenever it is desired to pass some articles, for instance, collars and cuffs, two 80 three times in succession between the rolls, in which case it is more convenient, and expeditious as well, for the operator to reach over and take up the articles from the rear table than to stoop down and pick them up from the chute or receiver below, each time he may want to repeat the pressing or mangling. The table 74 may be made of sheet-metal bound by wooden strips, as represented. Its rear edge is brought to bear on the uppermost rod 4, while its front edge is held by hooks 75, engaging studs 76, on the supports 5 and 6. This table is given a 85 gentle incline toward the lower roll, as 90 shown.

The cross-bar 10, hereinbefore referred to, is so placed with relation to the rolls and feed-table as to allow the clothes to pass freely under it and reach the rolls beyond, 100 and at the same time it keeps off the operator's hands just far enough to prevent his (or her) fingers from being caught and mashed between the rolls while feeding the clothes to the same. This safeguard favors 105 fast work inasmuch as the operator does not grope over it, feeling secure in the knowledge that mere incautiousness in bringing up the clothes to the rolls by pushing them with the hands as far as the cross-bar 110 will not result in personal injury.

It will be observed, upon referring to Figs. 1 and 2, that the lower roll 12 is located somewhat in advance or forward of the upper roll 11. This arrangement is preferred, first, because it leaves a larger portion of the lower roll exposed to receive the linen to be mangled, and secondly, because it permits the use of a shorter lever-arm to carry the lower roll, thereby insuring greater 115 pressure between the rolls with less effort on the longer lever-arm which the operator manipulates. It may be noted, further, that the gearing which rotates the rolls (Figs. 1, 3 and 4) can be transposed from one end of 120 the rolls to the other, as may be found convenient. The same is true of the heating device, which may be reversed in a similar manner to suit local requirements.

Having described my invention, what I 125

claim, and desire to secure by Letters Patent of the United States, is:

1. A machine of the character described having a pair of mangling instruments movable in parallelism one toward or away from the other, and means for controlling the application of pressure therebetween including an intermediately and yieldingly fulcrumed lever wherein the movable instrument is journaled, the fulcrum of said lever remaining permanently on the same side of the mangle.

2. In a machine of the character described, a surfacing-member and a padded pressing-member, one maintained in a relatively-fixed position and the other movable toward or away from the same, combined with a yieldingly-fulcrumed lever-system carrying and controlling the movable member, and a feed-table also carried by the lever-system and bearing a constant relation to the movable member during all changes of position in respect to the relatively-fixed member, said system including a pair of levers fitted for oscillation on yielding fulcra intermediate of their ends.

3. The combination, in a mangle, of a surfacing-roll, a pressure-roll, gears adapted to intermesh and positively rotate said rolls together, means including a lever wherein one of said rolls is journaled, an intermediate rocker for said lever, and a yielding support for said rocker.

4. The combination, in a mangle, of a pair of rolls arranged one above the other, means for governing the contact or distance and pressure therebetween including a plurality of levers having yielding fulcra remaining permanently on the same side of the mangle, and two tables arranged for operation substantially on a level one in front

and the other in rear of the rolls, the front table being secured to and moving with said levers, the rear table meanwhile remaining in position to receive the articles passed between said rolls approximately at said level.

5. A machine of the character described comprising two mangling rolls arranged one above the other, the upper roll retaining a relatively-fixed position and the lower roll being movable toward or away from the same, a cross-bar held in front of the relatively-fixed roll near the point of contact with the movable roll, a feed-table, and a yieldingly-fulcrumed lever-system supporting both the lower roll and feed-table and operating to move them together, below said cross-bar.

6. A machine of the character described comprising a chair-like frame, head-supports or standards rising from the arms or sides thereof, a pair of mangling rolls mounted between said standards, one roll being relatively fixed and the other movable in parallelism therewith, a yieldingly-fulcrumed lever-system including a pair of levers with which the movable roll is oscillated, said levers having each an intermediate yielding fulcrum and controlling the application of pressure between said rolls, a feed-table carried by said lever-system and movable with the same, and a chute or receiver extending from the back of the frame downward a suitable distance under the rolls and feed-table.

Signed at the city of New York, in the county of New York and State of New York this fifth day of September A.D. 1907.

J. H. THERIEN.
